UNITED STATES PATENT OFFICE.

WILLIAM C. RANNEY, OF ELBRIDGE, NEW YORK.

PAPER-ROLL HOLDER AND CUTTER.

1,330,005.

Specification of Letters Patent.

Patented Feb. 3, 1920.

Application filed November 20, 1919. Serial No. 339,428.

To all whom it may concern:

Be it known that I, WILLIAM C. RANNEY, a citizen of the United States, residing at Elbridge, in the county of Onondaga and State of New York, have invented certain new and useful Improvements Applied to Paper-Roll Holders and Cutters, of which the following is a specification.

Wrapping paper is now commonly furnished to the user in the form of rolls, and the support for such rolls is provided with a cutter bar under which the free end of the paper passes and against the edge of which the paper is drawn to facilitate tearing off the piece desired. It is often difficult to grasp the free edge of the paper, which usually lies close under the edge of the cutter bar after a piece has been torn off. My invention has for its object to furnish an attachment for turning the paper roll so as to carry the free edge of the paper a little beyond the cutter bar, and lifting it free from the surface of the roll in order that it may be conveniently grasped.

In the accompanying drawings in which the preferred form of my invention is illustrated—

Figure 1 is a perspective view of one end of a paper roll to which my invention is applied, the parts being in normal positions of rest.

Figs. 2 and 3 are end elevations showing other positions assumed by the parts when in use.

Fig. 4 is a front view, and

Fig. 5 is a sectional view on the line 5—5 of Fig. 4.

In the drawings, 2 indicates a roll of paper supported upon a shaft 3 that is mounted in a standard or supporting frame 4. The latter may be of any usual or preferred construction. 5 indicates a cutter bar suitably supported by the frame 4 and arranged to have its edge rest upon the periphery of the roll 2. Against such edge the paper is torn after being drawn from the roll.

6 represents a presser piece arranged to be made to bear upon the surface of the roll. It is adapted to have such engagement with the paper that when moved in the direction in which the periphery of the roll turns, it will cause the roll to turn with it. To this end the presser piece shown is provided with a series of points 7 adapted to slightly pierce the paper and prevent any relative

movement of the presser piece when it comes into engagement with the paper and is intentionally moved in a forward direction. The piece 6 normally lies close to or upon the surface of the roll not far distant from one of its ends and a little in front of the cutting edge of the bar 5. It is supported by an arm 8 of suitable construction. That illustrated in the drawings is formed of wire bent to form a handle 10 and the part 15 overlying the roll and directly carrying the presser piece 6. The main part of the arm 8 is arranged at the end of the roll, as represented in Figs. 1, 2 and 3 of the drawings, and is supported by a resilient hinge, or spring, 9, which is preferably quite flexible. The resilient hinge or spring is carried by a support 12, consisting preferably of a depending arm 13, and a horizontal arm 14 secured to the cutter bar.

11 represents a lifting plate carried by the supporting arm 8 and extending rearward from the presser piece 6. The presser piece and lifting plate may be integral, or separate, as preferred, the integral construction being illustrated in the drawings. The rear edge of this lifting plate bears at all times upon the surface of the roll 2.

It is to be understood that the cutter bar 5 is so supported as always to be in engagement with the roll, whatever its diameter, and it therefore forms a convenient support for the arm 12 carrying the presser piece and lifting plate. It is not essential that these parts be supported by the cutter bar so long as they are so mounted that they are always in proper working engagement with the roll, whatever its diameter, but the arrangement shown is preferred.

In Fig. 1 the parts that have been described are represented in their normal positions of rest. It will be seen that the free edge 16 of the paper is close under the cutting edge of the bar 5—so close that it can not be easily grasped by the fingers. The end of the lifting plate rests upon the surface of the roll just in advance of the free edge of the paper, while the presser piece lies slightly above the roll surface, where it is held by its resilient support. When it is desired to draw a piece of paper from the roll the first action is to move the parts from the position shown in Fig. 1 to that represented in Fig. 2, to do which the operator presses downwardly and forwardly upon the handle 10. This first brings the presser piece

into engagement with the roll surface a little in front of the free edge 16, the engagement being firm so that no slippage of the plate over the surface of the paper can take place, 5 by reason of the action of the points 7. This engagement of the presser piece with the roll surface having been established, the piece is moved forwardly to the position of Fig. 2, this being permitted by the fact that 10 the arm carrying the presser piece is supported by a resilient hinge or spring 9, allowing the movement described. As this movement takes place the roll is turned and the free edge 16 carried a sufficient distance 15 beyond the edge of the cutter bar to be easily grasped. The operator now releases the handle and the spring 9 restores the parts to normal positions, as represented in Fig. 3. In returning from the Fig. 2 to the Fig. 3 20 position the lifting plate slides under the free edge of the paper and raises it from the surface of the roll. In order to secure a good lifting action the plate 11 is curved or occupies a raised position with reference to 25 the surface of the roll, as represented in the drawings. The free end of the paper may be now easily grasped and the amount of paper required drawn off and torn from the roll in the usual manner, when the positions 30 of the parts will be again as represented in Fig. 1.

The presser piece 6 and the lifting plate 11 may be used either independently of the other, as well as conjointly, although the 35 latter use is preferred. For instance, the presser piece alone might be employed to turn the roll to advance the free edge of the paper beyond the cutter bar preparatory to its being grasped by hand, and this would be 40 advantageous over the now commonly employed practice of turning by the unaided hand, which is often difficult when the roll of paper is heavy, whereas by the use of a roll-surface-engaging part, of which the 45 piece 6 is an example, this turning is rendered comparatively easy. Again, the lifting plate that normally moves bodily in a curved path away from the cutter bar and coincident with the periphery of the roll, as 50 the roll is turned, could be used to advantage without the presser piece or roll-surface-engaging part that I have described, being carried forwardly to the roll as it is turned and being automatically returned toward 55 the presser bar to lift the free edge of the paper after the turning of the roll has ceased.

What I claim is:

1. The combination with a support for a

roll of paper and a cutter bar therefor, of 60 means adapted to engage with the roll for turning it, means for restoring said engaging means to normal position, and means for lifting the free edge of the paper as the engaging means are restored to normal position. 65

2. The combination with a support for a roll of paper and a cutter bar therefor, of 70 a presser piece adapted to be brought into firm, non-slipping engagement with the surface of the roll, and to be moved a short distance, turning the roll in a forward direction, means for automatically restoring the presser piece to normal position upon release, and means for lifting the free edge 75 of the paper upon the return movement of the presser piece.

3. The combination with a support for a roll of paper and a cutter bar therefor, of a presser piece adapted to be brought into 80 engagement with the peripheral surface of the roll for turnnig it, a support for the said presser piece normally holding it in advance of the cutter bar and the free edge of the paper, and movable to permit the piece to 85 bodily move with the roll as it turns it, a spring for restoring the presser piece to normal position, and a piece for lifting the free edge of the paper as the presser piece is restored to normal position. 90

4. The combination stated in claim 3, having the presser and edge lifting part united so as to be in effect one piece.

5. The combination stated in claim 3, having the support for the presser piece carried 95 by the cutter bar, and supporting the lifting piece as well as the presser piece.

6. The combination with a support for a roll of paper and a cutter bar therefor, of means for turning the roll to advance the 100 free edge of the paper beyond the cutter bar, comprising a roll-engaging piece bodily movable in a curved path coincident with the periphery of the roll as it is turned forward, and means for automatically restoring 105 it to normal position after it has been moved.

7. The combination with a support for a roll of paper and a cutter bar therefor, of a part for lifting the free edge of the paper arranged to bear upon the periphery of the 110 roll, in advance of the edge of the paper, and movable away from the cutter bar and with the roll as it is turned forwardly, and means for automatically returning the edge-lifting means to normal position and toward the 115 cutter bar after the forward movement of the roll has ceased.

WILLIAM C. RANNEY.
